UNITED STATES PATENT OFFICE.

NATHANIEL L. BARMORE, OF CHICAGO, ILLINOIS.

DESIGN FOR A CASKET OR SIMILAR HANDLE.

No. 38,606.

Specification for Design.

Patented June 4, 1907.

Application filed March 11, 1907. Serial No. 361,869. Term of patent 14 years.

To all whom it may concern:

Be it known that I, NATHANIEL L. BARMORE, a citizen of the United States, residing at Chicago, in the county of Cook and State of Illinois, have invented a new, original, and ornamental Design for Casket or Similar Handles, of which the following is a specification, reference being had to the accompanying drawings, forming a part thereof.

The figure is a front elevation of a casket handle, showing my new design;

I claim.

The ornamental design for a casket or similar handle as shown.

NATHANIEL L. BARMORE.
